GATE LOCK

Filed Feb. 14, 1929

UNITED STATES PATENT OFFICE

BENJAMIN HEYMAN, OF BALTIMORE, MARYLAND, ASSIGNOR TO ANCHOR POST FENCE COMPANY, OF JERSEY CITY, NEW JERSEY, A CORPORATION OF NEW JERSEY

GATE LOCK

Application filed February 14, 1929. Serial No. 339,826.

This invention relates to gate locking devices of the type wherein a vertical locking bar and a complementary keeper are employed.

5. In the preferred embodiment of my invention herein illustrated the locking bar is slidably supported on the free end of the gate structure and is movable into and out of locking relation with a suitably-disposed keeper. The bar is provided with a manual lifter having a lateral stub projecting toward the gate structure, and the latter is equipped with a fixture having a vertical guide channel for the stub. This channel terminates 10 at its lower portion in a recessed foot arranged and adapted to receive the stub when the locking bar is engaged with the keeper, thus enabling the stub and foot to be locked together by means of a padlock. One of the 15 walls of the channel is provided a suitable distance above the foot with a series of spaced teeth which are arranged and adapted to receive the stub and support the bar at different heights from the ground when the bar is 20 lifted from the keeper.

The invention comprises features of construction and combinations of parts which will be hereinafter described, and the scope of the invention then be defined in the appended claims.

In the drawings—

Figure 1 is a side elevation of a swinging gate equipped with locking mechanism embodying the preferred form of my invention.

35 Fig. 2 is a transverse section, enlarged, immediately above the lifter for the vertically-movable locking bar, as on the line 2—2 of Fig. 1.

Fig. 3 is a similar section at a higher level 40 when the locking bar is lifted from the keeper and supported in raised position.

Fig. 4 is a perspective view of the lifter detached from the locking bar.

45 Fig. 5 is a similar view of a guiding and supporting element adapted to co-operate with a laterally-projecting stub on the lifter.

Referring to the drawings, 10 designates a gate frame of any suitable construction hinged at one end, as at 11, to a post 12, and 50 equipped at the opposite end with a vertical

locking bar, 13 which is slidably fitted to guide fixtures 14 on the gate frame and is movable into and out of locking relation with a base socket 15 or other suitably-disposed keeper.

55 The lifting element preferably embodies a split collar or sleeve 16 which is suitably located on and permanently secured to the bar 13. This collar has integral therewith forwardly and rearwardly extending finger pieces 17 which facilitate the manipulation of the bar, and it is also provided with an integral radial stub 18 which extends toward and at a right angle to the adjacent end of the gate frame. The stub is preferably of 60 V-form in cross section, and has an upper angular shouldered portion 19 at its inner or basal end.

65 The guiding and supporting element embodies an elongated member 20 extending longitudinally of the gate frame. This member is formed with a vertical channel 21 which receives and guides the stub 18 of the locking bar. The lower portion of the channel terminates in a recessed or bifurcated 70

projecting foot 22 which is so located that it receives the stub 18 when the bar 13 is in its down position and in locking engagement with the socket or keeper. The walls of the 75

foot 22 are preferably rounded, as at 23, so as to co-operate with the tapering walls of the stub to facilitate the entrance of the latter into the foot. When the stub is thus seated in the foot, the shoulder 19 overhangs

80 the outer or free end of the foot. Hence the bow 24 of a padlock, as 25, can be readily hooked over the associated parts in the space between the shoulder and the heel of the foot, which bow, when the lock is snapped, effectively locks the stub and foot together,

85 thus preventing the lifting of the locking bar until the padlock is unlocked and removed.

90 The upper portion of the rearward wall of the member 20 is extended laterally, and is provided on its inner face with a series of transverse upwardly inclined teeth 26 with any of which the stub may be engaged when the bar is lifted and the gate unlocked. Thus 95 the bar can be supported with its lower end

at any desired elevation to enable it to clear the ground elevations, railroad rails, or other obstructions when the gate is being swung open.

5 While my invention is herein illustrated as embodied in a single gate it is obvious that it can be readily applied to double gates, and also that the construction may be modified within the principle of the invention and the scope of the appended claims.

10 I claim—

1. The combination with a gate structure, of a vertically-movable locking bar thereon, a keeper for the bar, a member extending fixedly from said bar toward the gate structure, a complementary member extending fixedly from the gate structure toward the said bar and adapted to be engaged with the first-named member when the bar is engaged with 20 the keeper, and means for locking together the associated members.

2. The combination with a gate structure, of a vertically-movable locking bar thereon, a keeper for the bar, a stub extending fixedly from said bar toward the gate structure, a recessed projection extending fixedly from the gate structure toward the said bar and adapted to receive the stub when the locking bar is engaged with the keeper, and means for locking together the said stub and gate projection.

3. The combination with a gate structure, of a vertically-movable locking bar thereon, a keeper for the bar, a stub extending fixedly from said bar toward the gate structure, a fixture on the gate structure having a vertical guide channel into which the stub projects, said channel terminating at its lower portion in a recessed projection adapted to receive the stub when the locking bar is engaged with 40 the keeper, and means for locking together the said stub and projection.

4. The combination with a gate structure, of a vertically-movable locking bar thereon, a keeper for the bar, a stub extending fixedly from the bar toward the gate structure, a recessed projection extending fixedly from the gate structure toward the said bar and adapted to receive the stub when the locking bar is engaged with the keeper, said stub having a shouldered portion which overlies the free end of the projection, and lock means including a bow for engaging said stub and projection between the shouldered portion and the gate structure.

5. The combination with a gate structure, of a vertically-movable locking bar thereon, a keeper for the bar, a lateral stub of V-cross-section extending from said bar toward the gate structure, and a relatively fixed projection on said structure having upstanding walls rounded at their upper edges and adapted to embrace the said stub when the locking bar is engaged with the keeper, and lock means including a bow for engaging said 65 stub and projection.

6. The combination with a gate structure, of a vertically-movable locking bar thereon, a keeper for the bar, a lifter fast on said bar and having a stub extending laterally toward the gate structure, a stub guiding and supporting fixture on the gate structure including a bifurcated foot arranged and adapted to receive the said stub when the locking bar is engaged with the keeper, and means for locking together said stub and foot.

7. The combination with a gate structure, of a vertically-movable locking bar thereon, a keeper for the bar, a lifter on said bar having a lateral stub extending toward the gate structure, and a stub guiding and supporting fixture on the gate structure, said fixture comprising an elongated body having a vertical stub-guiding channel terminating at its lower portion in a recessed foot adapted to receive the said stub when the locking bar is engaged with the keeper and having also a series of spaced teeth above said foot adapted to receive the stub and support the bar at different heights from the ground when the bar is lifted from the keeper.

8. The combination with a gate structure, of a vertically movable locking bar thereon, a keeper for the bar, a split collar connected to the bar, a stub on the collar extending toward the gate structure, and a projection connected to the gate structure extending toward the bar having a recess for the reception of the stub when the bar is in engagement with the keeper.

Signed at the city of Baltimore and State of Maryland this 12th day of February A. D. 1929.

BENJAMIN HEYMAN.
